UNITED STATES PATENT OFFICE.

CHARLES L. CURTIS, OF NEW YORK, N. Y., ASSIGNOR, BY MESNE ASSIGNMENTS, TO THE NORDLINGER-CHARLTON FIREWORKS COMPANY, OF SAME PLACE.

FIRE-CRACKER-CHOKING MACHINE.

SPECIFICATION forming part of Letters Patent No. 634,201, dated October 3, 1899.

Application filed February 7, 1898. Serial No. 669,370. (No model.)

To all whom it may concern:

Be it known that I, CHARLES L. CURTIS, a citizen of the United States, residing at the city of New York, (Brooklyn,) county of Kings, and State of New York, have invented a new and useful Fire-Cracker-Choking Machine, of which the following is a specification.

The object of my invention is to provide a machine capable of securely closing or choking the ends of the bore in a fire-cracker, so as to retain a charge therein, and in this connection the machine is adapted to upset or compress the material of the fire-cracker that closely surrounds the bore, so as to cause such material to project over the bore, thus forming a closure for the latter.

The invention consists in a machine comprising a support for a fire-cracker, the stem or rod adapted to enter the bore of a fire-cracker, and a plunger adapted to upset the material of the fire-cracker that surrounds the bore, whereby an opening will be left for the stem of the fire-cracker.

25 The invention also consists in a machine comprising a support for a fire-cracker, a head adapted to be pressed against the end of the fire-cracker and provided with prongs that are adapted to enter the material of the fire-cracker to loosen the same around the bore thereof, and a plunger adapted to upset or compress such loosened material to choke the bore of the fire-cracker.

30 The invention also consists in the novel details of improvement and the combinations of parts, that will be more fully explained hereinafter and then pointed out in the claims.

Reference is to be had to the accompanying drawings, forming part hereof, wherein—

40 Figure 1 is a side elevation, partly broken, of a machine for choking fire-cracker bores embodying my invention. Fig. 1^a is a detail side view, enlarged, of the head and prongs that are adapted to act upon the end of the fire-cracker. Fig. 1^b is a vertical section thereof. Fig. 1^c is a horizontal section on the line x x of Fig. 1^a. Fig. 1^d is an end view of the head shown in Fig. 1^a, looking at the lower portion thereof. Fig. 2 is an enlarged 45 vertical sectional view of the operative portions of the machine in their normal inopera-

tive positions. Fig. 3 is a similar view showing the parts in the positions they assume when the head is brought to rest upon the fire-cracker. Fig. 4 is a similar view showing the positions of the parts when the operation of choking the bore in the fire-cracker is completed. Fig. 5 is an enlarged detail side elevation of the upper portion of the machine, showing it as arranged to choke the end of the fire-cracker after it has received the charge and the stem; and Fig. 6 is a detail plan view of a support for the fire-cracker adapted to receive the stem while the opposite end is being choked.

In the accompanying drawings, in which similar numerals of reference indicate corresponding parts in the several views, 1 indicates a standard or column having a base 2, all of which may be of suitable construction.

3 3 is a bracket or support carried by the standard 1, and by preference it is made adjustable, for which purpose it is provided with a removable clamp-piece 4, the parts 3 4 having webs 3^a 4^a to receive bolts 5 for clamping it securely upon the column or standard.

6 6 is a support for a fire-cracker, which is carried by the bracket 3 and is preferably made movable laterally, and for this purpose the support 6 is shown located in a recess 7 in 8 said bracket and mounted upon a pivot 8, carried by the latter in such manner that the support 6 can be swung outwardly, as indicated in dotted lines in Fig. 3, to enable a fire-cracker to be applied thereto. The support 6 is shown provided with a head-like portion 6^a of sufficient area to properly receive a fire-cracker of such diameter as the machine is adapted for. The support 6 is also provided with a guide or stem 9, that is adapted 9^a to enter the bore in a fire-cracker 10. As shown in Figs. 1, 2, 3, and 4, the guide or stem 9 is quite long, so as to project well into the fire-cracker, and at its outer or upper end the guide or stem 9 is shown provided with a recess 9^a to receive a plunger, as will be explained hereinafter.

By preference the guide or stem 9 is detachably connected with support 6, and for this purpose it is provided with screw-threads 9^b to mesh with corresponding threads in support 6. (See Fig. 2.)

With the parts so far described when it is

desired to adjust a fire-cracker in the machine in position to be operated upon the support 6 is swung outwardly, the fire-cracker is passed over the guide or stem 9 to rest upon head 6^a, 5 and the support is then swung back into operative position, as clearly shown in Fig. 3.

Above the support 6 are the devices for choking the ends of the bore in the fire-cracker. These devices are arranged as follows:

Upon column or standard 1 is secured a casting or head 11, which is shown provided with a bracket-like offset 12, that has a bearing or bore 12^a, alined with the guide or stem 9, and the head 11 also has a cavity or recess 13 to receive levers 14 15, which are shown mounted on spindles 14^a 15^a, supported by the head 11. In the bearing 12^a is mounted a slide 16, which is adapted to reciprocate therein, and at its lower end said slide carries a head 17, that is adapted to be pressed upon the fire-cracker 10, as shown in Fig. 3. The head 17 is shown as removably connected with slide 16, and for this purpose it is connected therewith by means of screw-threads 18. The head 17 carries a series of prongs or fingers 19, arranged in circular form and in such manner as to encircle the bore in the fire-cracker. These prongs or fingers are shown in the form of wires passing through a bore 17^a in the head 17, and they are provided with outwardly-extending portions 20, that enter holes 21, that extend transversely through the head 17 and register with the bore 17^a in said head. By this means the prongs or fingers 19 are made interchangeable. The lower ends of said prongs or fingers 19 are shown beveled from their inner sides downwardly and outwardly at 19^a in such manner that when they enter the material of the fire-cracker they will act to not only loosen the same, but to press said material inwardly or toward the bore therein. Thus when the head 17 is brought down upon the fire-cracker 45 the prongs 19 enter the material thereof, loosen the convolutions of the fire-cracker body, and force the same inwardly and partially over the bore of the fire-cracker. Within the bore 17^a of head 17 is a plunger 22, that 50 is adapted to have movement independently of the movement of said head, and said plunger is located partially within a bore 16^a in slide 16. The plunger 22 on its periphery is provided with a series of longitudinal recesses 22^a, in which the prongs or fingers 19 are located, whereby said plunger is kept from rotating, while permitted longitudinal movement independently of said prongs or fingers. The plunger 22 is adapted to engage 55 the end of the fire-cracker and to upset or compress the material thereof, so as to choke the end of the bore in the fire-cracker, as clearly shown in Figs. 3 and 4. The plunger 22 is also provided with a central longitudinal bore 23, adapted to receive a rod or stem 24, that is adapted to enter the bore in the fire-cracker, and is also adapted to enter the socket

or recess 9^a in guide or stem 9. By preference the rod 24 is detachably connected with the plunger 22, and the plunger 22 is preferably detachably connected with a rod 25, that is located within the bore 16^a of slide 16, so that it may slide longitudinally therein. The plunger 22 is shown provided with screw-threads 22^b, that mesh with corresponding threads in the end of rod 25, and the rod 24 is shown provided with threads 24^a, that mesh with corresponding threads in the plunger 22. The rod 24 is shown as having an enlarged threaded portion at 24^a, a reduced portion at 24^b, and a still further reduced portion at 24^c, that enters the fire-cracker bore. By this means the plunger 22 and the rod 24 are made interchangeable, and whereby also the prongs or fingers 19 are interchangeable, so the parts 85 may be changed when worn.

Any suitable means may be provided for reciprocating the slide 16 and the rod 25. I have shown the slide 16 as provided with recesses 16^b to receive the bifurcated end 14^b of lever 14, the operative edges of which lever are preferably rounded to work properly against the material of the slide 16. The end 14^c of lever 14 is adapted to be operated by a cam 26. The cam 26 is supported by a spindle 27, carried by a bracket 28, extending from head 11. The cam 26 has a recess 26^a, adapted to receive the end of lever 14 or a roller 29, carried by said lever, whereby when said roller (or the end of the lever) is in said recess the lever 14 will be tilted, so as to elevate the slide 16 to its highest point. The cam 26 has gear-teeth 30, that mesh with a toothed rack or slide 31, that is guided in a suitable recess or slideway 32 in head 11. The rack 31 is pivotally connected with a rod 33, that is pivoted to a treadle 34, pivotally supported at 35 by the standard or column 1 (see Fig. 1) in such manner that when the operator depresses said treadle the rod 33 and rack 31 will be pushed up, and thereby rotate cam 26 in the direction of the arrow in Fig. 2. When the cam is so rotated, it acts upon roller 29 to lift the outer end of lever 14 and depress the opposite end of said lever, thereby forcing down the head 17 upon the fire-cracker, as shown in Fig. 3.

The rod 25 is reciprocated independently of slide 16 through the medium of lever 15 and rack 31, and for this purpose said rod 25 is shown provided with a recess 25^a, in which the end 15^b of lever 15 projects, the edges of said lever being rounded and fitting snugly within said recess 25^a. The slide 16^a has a longitudinal slot 16^d, through which the lever 15 projects, whereby the parts 15 and 16 may operate independently. The end 15^c of lever 15 overlies the upper end of rack 31 in such position that as said rack is raised by treadle 34 the end 15^c of lever 15 will be raised, and as the opposite end of said lever descends rod 25 will be pushed downwardly to pass the rod or stem 24 into the bore of the fire-cracker body and into the recess 9^a in guide 9, while

at the same time plunger 22 is forced against the material of the fire-cracker that lies beneath it to upset or compress the same. Lever 15 is acted upon by a spring 36 to hold the 5 end 15^c against rack 31, and to thus normally hold the rod 25, head 17, plunger 22, and rod 24 elevated in the normal positions shown in Fig. 2. The upper end of rod 25 is shown provided with screw-threads 37, that receive 10 a stop or nut 38, that is adapted to be brought to bear against the extension or bracket 12 as rod 25 descends, and this nut may be adjusted lengthwise of nut 25 to determine the distance that the plunger 22 can be forced down- 15 wardly into the fire-cracker body.

The parts so far described are illustrated in Figs. 1 to 4, inclusive, and as arranged they are adapted to choke that end of the fire-cracker from which the stem projects. 20 After the end is choked, as shown in Fig. 4, the fire-cracker body is removed from the guide 9 and filled with a charge 10^a, and a stem 10^b is inserted in the hole left in the end of the fire-cracker by the rod 24, and then the 25 fire-cracker is adjusted in another machine substantially similar to the one described, but with the following exceptions: The guide 9 is short, but of just sufficient length to enter the bore in the fire-cracker at the part outside of 30 the upset end 10^c, as shown in Fig. 5, and said guide 9 and the head 6^a are provided with a slot or recess 6^b to receive the stem 10^b, and by preference this slot or recess extends from the center of the head 6^a to the outer edge 35 thereof, so that the stem may be passed in sidewise. (See Fig. 6.) 39 is a bracket secured to head 11 and provided with a recess 39^a, that is preferably concave on its outer face to enable the side of the fire-cracker 10 40 to rest against it, whereby it assists in retaining the fire-cracker in upright position upon the support 6. These brackets 39 may be detachably connected with the head 11 and the concave face at 39^a of different brackets may 45 be arranged to correspond to the periphery of various-sized fire-crackers for the purpose of holding the different fire-crackers firmly in position.

While it is preferable to have one machine 50 arranged as shown in Figs. 1 to 4 for the first operation and another machine arranged as shown in Figs. 5 and 6 for the final operation, it is evident that the first-mentioned machine may be arranged so that the parts 9 and 39 55 may be detachably connected therewith to enable the operations to be performed on opposite ends of the fire-cracker; but by having one machine arranged to complete one end of the fire-cracker and another machine 60 arranged for the opposite end thereof time can be saved in completing the fire-cracker.

The operation is as follows: When the parts 65 are in their normal positions, as shown in Figs. 1 and 2, and it is desired to choke the end of a fire-cracker, the support 6 and guide 9 are first swung outwardly, as shown in dotted lines in Fig. 3, and the fire-cracker is

then passed over the guide 9, so as to rest upon the support 6 6^a. Said support is then moved back into its normal position, so as 70 to bring the fire-cracker directly beneath the head 17, and thereupon the treadle 34 is operated, whereupon rack 31 is raised, which causes cam 26 to rotate and also lifts lever 15 direct. The rotation of cam 26 first causes 75 head 17 to descend upon the fire-cracker 10, whereupon the prongs or fingers 19 pass into the fire-cracker, loosen the convolutions thereof, and press such convolutions inwardly at the beveled lower ends of prongs or fingers 19, as shown in Fig. 3, the movement of head 17 through the medium of cam 26 being faster than the movement of rod 25 and plunger 22. A continued movement of rack 31 upwardly causes lever 15 to press rod 25 85 downwardly, whereupon rod 24 enters the bore in the fire-cracker, and as said rod projects beyond head 24 it enters said fire-cracker almost simultaneously with the entrance of prongs 19 therein. A continued depression of rod 25 causes plunger 22 to act upon the material of the fire-cracker that surrounds the bore therein and which lies within the space bounded by prongs 19, whereupon such material is compressed in a solid mass, 95 so as to choke the bore in the fire-cracker excepting at the part where the rod 24 enters the same. The treadle is then released, and rod 25, plunger 22, rod 24, head 17, and prongs 19 rise from the fire-cracker, thus leaving one end of the fire-cracker choked with a small aperture, aligned with the bore of the fire-cracker, produced by the presence of rod 24 and adapted to receive the stem 10^b. The fire-cracker is then removed from guide 9, 100 the stem and charge are inserted, and the fire-cracker inverted from its previous position and placed upon the support 6 and guide 9, as shown in Fig. 5, directly beneath the head 17. The treadle 34 is thereupon again 105 operated, which causes rack 31 to operate cam 26 and levers 14 15 in manner before explained to choke the upper end 10^d of the fire-cracker (shown in Fig. 5) in manner similar to that shown and described with relation 110 to Fig. 4, the prongs 19 and plunger 22 acting to choke the end of the bore of the fire-cracker over the charge. It will be understood, however, in this connection that when this last-mentioned choking of the fire-cracker 115 bore is effected the rod 24 is not present, so that there will be no hole left in the end of the fire-cracker, as described, where it is desired to leave a space for the stem 10^b. When the second end of the fire-cracker is thus 120 choked, it will be removed from the support 6 125 ready for use or packing, as may be desired.

I do not limit my invention to the precise details of construction and arrangement shown and described, as they may be varied without departing from the spirit thereof.

Having now described my invention, what I claim is--

1. A fire-cracker-choking machine compris-

- ing a support for a fire-cracker body, a movable head having its operative end arranged on a plane perpendicular to its axis to bear on the end of the body and having prongs wholly within the circumference of the head and projecting therefrom, said prongs having inwardly-beveled points, and means for forcing said prongs into the end of the said body, substantially as described.
10. 2. A fire-cracker-choking machine comprising a support for a fire-cracker body, a movable head having a plurality of separated prongs projecting therefrom, said prongs having inwardly-beveled points, a plunger, and means whereby the prongs are first forced into the material of the body to upset it and the upset portion is next forced inwardly by means of the plunger, substantially as described.
15. 3. A fire-cracker-choking machine comprising a support for a fire-cracker, a plunger opposite said support adapted to enter the fire-cracker to upset the material thereof, means to form a bore for a stem in the upset portion 25 of said body, and means for operating said plunger, substantially as described.
20. 4. A fire-cracker-choking machine comprising a support for a fire-cracker, a head adapted to bear upon the fire-cracker, a plunger 30 movable independently of said head and adapted to upset the material of the fire-cracker, and means for operating said head and plunger, substantially as described.
25. 5. A fire-cracker-choking machine comprising a support for a fire-cracker, a plunger adapted to upset the material of the fire-cracker, a rod adapted to enter the bore of the fire-cracker to provide an opening therein 35 for a stem, and means for operating said plunger and rod, substantially as described.
30. 6. A fire-cracker-choking machine comprising a support for a fire-cracker, a head adapted to bear upon the fire-cracker, a plunger adapted to upset the material of the fire-cracker, a rod adapted to enter the bore of the fire-cracker, and means for operating said head, plunger, and rod, substantially as described.
35. 7. A fire-cracker-choking machine comprising a support for a fire-cracker, a guide connected with said support to retain the fire-cracker in operative position, a plunger adapted to upset the material of the fire-cracker, means to form a bore for a stem in the upset portion of said body, and means for operating said plunger, substantially as described.
40. 8. A fire-cracker-choking machine comprising a support for a fire-cracker, a guide adapted to retain said fire-cracker in operative position, a head adapted to bear upon the fire-cracker, and a plunger movable independently of said head and adapted to upset the material of the fire-cracker, substantially as described.
45. 9. A fire-cracker-choking machine comprising a support for a fire-cracker, a guide connected with said support adapted to enter the bore of the fire-cracker, a head adapted to bear upon the fire-cracker, a plunger adapted to upset the material of the fire-cracker, a rod adapted to enter the bore of the fire-cracker, and means for operating said plunger and rod, substantially as described.
50. 10. A fire-cracker-choking machine comprising a support for a fire-cracker, a guide connected with said support adapted to enter the bore of the fire-cracker and having a recess at its outer end, a head adapted to bear upon the fire-cracker, a plunger adapted to upset the material of the fire-cracker, a rod adapted to enter the bore of the fire-cracker and the recess in said guide, and means for operating said plunger and rod, substantially as described.
55. 11. A fire-cracker-choking machine comprising a support for a fire-cracker, a guide connected with said support adapted to enter a fire-cracker bore and having a recess at its outer end, a head adapted to bear upon the fire-cracker, a plunger adapted to upset the material of the fire-cracker, a rod adapted to enter the bore of the fire-cracker and the recess in said guide, and means for operating said plunger and rod, substantially as described.
60. 12. A fire-cracker-choking machine comprising a support for a fire-cracker, a head adapted to bear upon the fire-cracker, fingers or prongs carried by said head adapted to enter the material of the fire-cracker to loosen it, and a plunger adapted to enter and upset the material of the fire-cracker, substantially as described.
65. 13. A fire-cracker-choking machine comprising a support for a fire-cracker, a head adapted to bear upon the fire-cracker, fingers or prongs carried by said head and arranged in a circle and adapted to enter the material of the fire-cracker to loosen it, a plunger located within the circle of the prongs or fingers, and means for operating said head and plunger independently, substantially as described.
70. 14. A fire-cracker-choking machine comprising a support for a fire-cracker, a head adapted to bear upon the fire-cracker, fingers or prongs carried by said head adapted to enter the material of the fire-cracker to loosen it, said fingers or prongs having their lower ends beveled downwardly and outwardly, a plunger adapted to upset the material of the fire-cracker, and means for operating said head and plunger independently, substantially as described.
75. 15. A fire-cracker-choking machine comprising a support for a fire-cracker, a head adapted to bear upon the fire-cracker, said head having a bore, a plunger adapted to travel in said bore and having an axial rod to enter the bore in the fire-cracker, and means for operating said plunger independently of the head to force it into the fire-cracker with the rod, substantially as described.

16. A fire-cracker-choking machine comprising a support for a fire-cracker, a head adapted to bear upon the fire-cracker, said head having a bore, prongs or fingers carried by said head adapted to enter a fire-cracker, a plunger located in the bore of said head, and means for operating said plunger independently of the head, substantially as described. 70
17. A fire-cracker-choking machine comprising a support for a fire-cracker body, a rod on the support to enter the body, a head carrying prongs or fingers having inwardly-beveled points, and means for moving said prongs into the material of the body to move the latter toward the top of said rod, substantially as described. 75
18. A fire-cracker-choking machine comprising a support for a fire-cracker, a guide connected with said support adapted to retain the fire-cracker in operative position, a head adapted to bear upon the fire-cracker, said head having a bore, a plunger adapted to travel in said bore, a rod extending from said plunger adapted to enter the bore in the fire-cracker, and means for operating said plunger and rod independently of the head, substantially as described. 80
19. A fire-cracker-choking machine comprising a support for a fire-cracker, a guide connected with said support adapted to enter the bore of the fire-cracker, said guide having a recess at its outer end, a head adapted to bear upon the fire-cracker, said head having a bore, a plunger adapted to travel in said bore, a rod extending from said plunger to enter the recess in the guide, and means for operating said plunger and rod independently of the head, substantially as described. 85
20. A fire-cracker-choking machine comprising a support for a fire-cracker, a head adapted to bear upon a fire-cracker, said head having a bore and apertures extending crosswise of said head and opening into said bore, prongs or fingers having bent portions located in said apertures and also located in said bore, a plunger located in said bore and adapted to travel therein, and means for operating said plunger independently of the head, substantially as described. 90
21. A fire-cracker-choking machine comprising a support for a fire-cracker, a head adapted to bear upon the fire-cracker, said head having a bore and apertures extending crosswise of said head and opening into said bore, prongs or fingers having bent portions located in said apertures and also located in said bore, a plunger located in said bore, a rod extending from said plunger, and means for operating said plunger and rod independently of the head, substantially as described. 95
22. A fire-cracker-choking machine comprising a support for a fire-cracker, a head adapted to bear upon the fire-cracker, said head having a bore, prongs or fingers located in said bore, a plunger also located in said bore and having longitudinal grooves to receive said prongs or fingers, and means for operating said plunger independently of the head, substantially as described. 100
23. A fire-cracker-choking machine comprising a support for a fire-cracker, a head adapted to bear upon the fire-cracker, said head having a bore, prongs or fingers located in said bore, a plunger also located in said bore and having longitudinal grooves to receive said prongs or fingers, a rod extending from said plunger and adapted to enter the bore of the fire-cracker, and means for operating said plunger and rod independently of the head, substantially as described. 105
24. A fire-cracker-choking machine comprising a support for a fire-cracker, a head adapted to bear upon the fire-cracker, said head having a bore, a plunger located in said bore, said plunger having a bore, a rod located in the last-mentioned bore and detachably connected with said plunger, and means for operating said plunger independently of the head, substantially as described. 110
25. In a fire-cracker-choking machine the combination of a standard, a support for a fire-cracker movably connected therewith, a head located above said support and adapted to bear upon the fire-cracker, a plunger movable independently of said head and adapted to upset the material of the fire-cracker, and means for operating said head and plunger independently, substantially as described. 115
26. In a fire-cracker-choking machine the combination of a standard, a bracket adjustably carried thereby, a support movably connected with said bracket and adapted to support a fire-cracker, a head adapted to bear upon the fire-cracker, a plunger adapted to upset the material of the fire-cracker, and means for operating said head and plunger, substantially as described. 120
27. In a fire-cracker-choking machine the combination of a standard, a bracket adjustably carried thereby, a support for a fire-cracker pivotally carried by said bracket, a head adapted to bear upon the fire-cracker, a plunger adapted to upset the material of the fire-cracker, and means for operating said head and plunger, substantially as described. 125
28. In a fire-cracker-choking machine the combination of a standard, a bracket carried thereby and having a recess or socket, a support pivotally carried by said bracket and located in said recess or socket and adapted to support a fire-cracker, a head adapted to bear upon the fire-cracker, a plunger adapted to upset the material of the fire-cracker, and means for operating said head and plunger, substantially as described. 130
29. In a fire-cracker-choking machine the combination of a standard, a support for a fire-cracker, a head upon said standard, a slide carried by said head, a head connected with said slide and adapted to bear upon the fire-cracker, a plunger movable independently

of the head adapted to upset the material of the fire-cracker, and means for operating said slide and plunger, substantially as described.

30. In a fire-cracker-choking machine the combination of a standard, a support for a fire-cracker adjustably carried thereby, a head carried by said standard, a slide carried by said head and having a bore, a head 17 carried by said slide, a rod within the bore of said slide, a plunger carried by said rod, and means for operating said slide and rod independently, substantially as described.

31. In a fire-cracker-choking machine the combination of a standard, a support for a fire-cracker carried thereby, a head carried by said standard, said head having a bearing 12^a, a slide located in said bearing and having a bore, a head 17 carried by said slide and provided with prongs or fingers, a rod within the bore of said slide, a plunger connected with said rod and means for operating said slide and rod independently, substantially as described.

32. In a fire-cracker-choking machine the combination of a standard, a support for a fire-cracker carried thereby, a head carried by said standard, said head having a bearing 12^a, a slide located in said bearing and having a bore, a head 17 carried by said slide and provided with prongs or fingers, a rod within the bore of said slide, a plunger connected with said rod, means for operating said slide and rod independently, and an adjustable stop carried by said rod adapted to limit the movement of said rod in the operative direction, substantially as described.

33. In a fire-cracker-choking machine the combination of a standard, a support for a fire-cracker carried thereby, a head carried by said standard, said head having a bearing 12^a, a slide located in said bearing and having a bore, a head 17 carried by said slide and provided with prongs or fingers, a rod within the bore of said slide, a plunger connected with said rod, means for operating said slide and rod independently, said rod having threads 37, and a nut engaging said threads to regulate the movement of said rod in the operative direction, substantially as described.

34. In a fire-cracker-choking machine the combination of a standard, a support for a fire-cracker carried thereby, a head carried by said standard, said head having a bearing, a slide within said bearing, a pressing or holding head carried by said slide, a plunger, a lever adapted to operate said slide, means for operating said lever, and means for operating said plunger, substantially as described.

35. In a fire-cracker-choking machine the combination of a standard, a support for a fire-cracker, a head carried by said standard and having a bearing, a slide located in said bearing, a head 17 carried by said slide, a plunger, a lever adapted to operate said slide, a cam adapted to operate said lever, means for operating said cam, and means for operating said plunger, substantially as described.

36. In a fire-cracker-choking machine the combination of a standard, a support for a fire-cracker, a head carried by said standard and having a bearing, a slide within said bearing, a head 17 carried by said slide, a plunger, a lever adapted to operate said slide, a cam having a recess to receive said lever, said cam having teeth, a rack adapted to engage said teeth, means for operating said rack, and means for operating said plunger, substantially as described.

37. In a fire-cracker-choking machine the combination of a standard, a support for a fire-cracker carried thereby, a head carried by said standard and having a bearing, a slide within said bearing and provided with a bore, a head 17 carried by said slide, means to operate said slide, a rod within the bore of said slide, a plunger connected with said rod, a lever to operate said rod, means for operating said lever, and means for operating the slide, substantially as described.

38. In a fire-cracker-choking machine the combination of a standard, a support for a fire-cracker, a head upon said standard and having a bearing, a slide within said bearing provided with a bore, a head carried by said slide, means for operating said slide, a rod within the bore of said slide, a plunger carried by said rod, a lever to operate said rod, a treadle and connections to operate said lever, and a spring to act with said lever, substantially as described.

39. In a fire-cracker-choking machine the combination of a standard, a support for a fire-cracker carried thereby, a head upon said standard and having a bearing, a slide located in said bearing and having a bore, a head carried by said slide, a rod within said bore, a plunger connected with said rod, a lever to operate said slide, a lever to operate said rod, a cam to operate the first-mentioned lever, and means for simultaneously operating said cam and the second-mentioned lever, substantially as described.

40. In a fire-cracker-choking machine the combination of a standard, a support for a fire-cracker carried thereby, a head upon said standard and having a bearing, a slide within said bearing and having a bore, a head carried by said slide, a rod within said bore, a plunger carried by said rod, a lever to operate said head, a cam to operate said lever, said cam having teeth, a rack to operate said cam, a lever to operate said rod, said rack being adapted to operate the last-mentioned lever, and means for operating said rack, substantially as described.

41. In a fire-cracker-choking machine the combination of a standard, a support for a fire-cracker carried thereby, a head upon said standard and having a bearing, a slide provided with a bore and with a longitudinal slot leading to said bore, a head carried by said slide, a rod within said bore, a plunger carried by said rod, a lever for operating said slide, a lever for operating the rod and located

in the slot of said slide, and means for operating said levers simultaneously, substantially as described.

42. In a fire-cracker-choking machine the combination of a standard, a support for a fire-cracker carried thereby, a head upon said standard and having a bearing, a slide within said head, a head 17 detachably connected with said slide, said slide having a bore, said head having a bore, a rod within the bore of said slide, a plunger carried by said rod and located within the bore of said head, and means for operating said slide and said rod independently and simultaneously, substantially as described.

43. A fire-cracker-choking machine comprising a support for a fire-cracker having a guide and an opening to receive a stem, a bracket to support the fire-cracker, a head to

bear upon the fire-cracker, a plunger to upset the material of the fire-cracker and means for operating said head and plunger, substantially as described.

44. A fire-cracker-choking machine comprising a support for a fire-cracker having a guide and a slot or recess in said guide and support to receive a stem, a bracket to sustain a fire-cracker, a head to bear upon the fire-cracker, a plunger to upset the material of the fire-cracker, and means for operating said head and plunger, substantially as described.

Signed at the city, county, and State of New York this 4th day of February, 1898.

CHARLES L. CURTIS.
